(57) **CLAIM**

I claim the ornamental design for an controller for electric fence, as shown and described.

DESCRIPTION

FIG. 1 is a Perspective view of an controller for electric fence showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof; and,

FIG. 7 is a Bottom view thereof.

The broken lines in the drawings depict portions of the controller for electric fence that form no part of the claimed design.
